UNITED STATES PATENT OFFICE.

DAVID H. GRIFFITH, OF WILMINGTON, DELAWARE.

SAFETY DEVICE AND DRAIN ATTACHMENT FOR LOCOMOTIVE-SUPERHEATERS.

1,122,912.

Specification of Letters Patent.

Patented Dec. 29, 1914.

Application filed October 11, 1912. Serial No. 725,824.

To all whom it may concern:

Be it known that I, DAVID H. GRIFFITH, a citizen of the United States, residing at Wilmington, in the county of New Castle and State of Delaware, have invented new and useful Improvements in Safety Devices and Drain Attachments for Locomotive-Superheaters, of which the following is a specification.

10 This invention relates to a safety device and drain for locomotive superheaters, and the primary object of the same is to provide simple and effective means for liberating steam that may remain in the superheater after the throttle valve has been shut off and also for liberating steam that may be generated by water of condensation settling in various parts or connections communicating with the superheater and in the latter in 15 firing up when the locomotive is standing, or, in preparing the latter for a run, and thereby overcome lack of control and avoid accidents due to steam that may remain in the superheater or be generated in parts of 20 the boiler and the superheater and outside 25 of the control of the throttle valve.

The invention consists in the construction and arrangement of parts which will be more fully hereinafter described and claimed and 30 illustrated in preferred form in the accompanying drawings, wherein:—

Figure 1 is a longitudinal sectional elevation of a portion of a locomotive boiler showing the improved safety device or attachment applied thereto. Fig. 2 is a cross-sectional view through a locomotive boiler, the running boards and part of the framework, illustrating a portion of the boiler broken away.

40 The numeral 5 designates a locomotive boiler of a well known type of construction embodying a superheater 6 with pipes 7 running rearwardly into the flues 8 and a supply pipe 9 which runs back to the steam dome 45 and is supplied with the usual form of throttle valve and an operating means extending backwardly into the cab of the locomotive. Extending from the superheater 6 are cylinder feed pipes 10 connecting with 50 the cylinders 11 in the usual manner, it be-

ing understood that there are two of these pipes 10 or one for each cylinder.

The parts just described are well known in locomotive construction and are believed to be sufficient to demonstrate the application and operation of the safety device or drain for the superheater which will be now explained. Attached to the bottom of the superheater 6 are drain pipes 12, the upper ends of these pipes communicating with the body of the superheater immediately in rear and close to the points of attachment of the cylinder feed pipes 10. The drain pipes 12 extend downwardly through the boiler 5 and then exteriorly of the latter as shown by Fig. 2 and are preferably curved under the boiler inside of the cylinders and in rear of the saddle, and each terminates in a drain valve 13 having an operating lever 14, all as clearly shown by Fig. 2. In rear of the cylinders and saddle of the engine and extending through and having bearing in opposite portions 15 of the frame is a rock shaft 16 provided with arms 17 extending upwardly and movably attached to the levers 14. At one end of the shaft 16, an operating lever 18 is secured and has a connecting rod 19 attached to the upper end thereof and extending rearwardly under one of the foot-boards 20 to the engine cab 80 where it will be provided with a suitable operating lever or other means for longitudinally shifting the same in opposite directions to simultaneously open or close the drain valves or cocks 13.

85 The improved safety device or drain attachment may be readily applied to the locomotive and connected up to the superheater without requiring any modification of the usual organization of superheater attachments, the superheater shown in the drawings being of the Schmidt type. It will be understood, however, that the safety device or drain attachment embodying the features of the invention may be equally well used with other superheaters.

90 The operation of the superheater is well known in the art of locomotive engineering, but it embodies disadvantages which the improved attachment has been devised to over- 100

come, and among others may be stated the inability of control, through the throttle valve or any other means, of the steam that may remain in the supply pipe 9 and other parts of the superheater after the throttle valve has been shut off and the condensation of the residual steam within the flues, and a subsequent generation of steam when the locomotive is fired up prior to a run and 10 after it has been resting or in disuse as, for instance, in a round-house or at any other point, and this failure to control the residual steam or steam generated from water of condensation in the flues or other parts of 15 the superheater has resulted in annoyances and accidents by reason of the fact that this residual steam, as well as the steam generated from the water of condensation in the flues and other parts of the superheater, is 20 free to pass through the feed pipes 10 into the cylinders and start the locomotive in motion.

By the use of the improved safety device or drain attachment, the engineer or driver 25 of the locomotive, after the throttle valve has been shut off or closed, may immediately open the drain valves or cocks 13 by operating the rod 19 and through the lever 18 actuating the shaft 16 to cause the arms 17 to 30 move the valve levers 14 into a position to open the said valves or cocks, and as a consequence, all of the residual steam in the superheater will be permitted to blow out or escape to the exterior of the boiler at points 35 below the latter and between the cylinders in rear of the saddle, and by this escape, settling of the steam and condensation thereof in the flues is prevented, and, furthermore, such steam instead of passing into the cylinders 40 will escape to the atmosphere as the ventage therefor through the medium of the pipes 12 is in rear of the points of connection or attachment of the feed pipes 10 to the superheater, as hereinbefore explained. 45 A further function of the attachment is to liberate the tubes of collected water therein that may result from an overflow of the boiler in filling the latter. Such water remaining in the tubes would be converted 50 into steam which would flow down into the cylinders as it could not be controlled by the throttle valve. The object in locating the valves or cocks 13 under the boiler in planes between the cylinders and in rear of the saddle is to direct the steam exhausted from the superheater downwardly under the boiler so 55 that there may be no inconvenience from such steam escaping at points adjacent to the outer portions of the cylinders. 60 The improved safety device or drain attachment is comparatively inexpensive in its structure and cost of application and the advantages accruing from its use will more than compensate for its cost in that accidents to locomotives, due to the uncontrolled 65

steam remaining in the superheater, will be avoided.

What is claimed is:

1. In a locomotive engine, the combination with a boiler, a superheater therein, and a steam supply pipe, of a header having a horizontal chamber with a flat bottom having the supply pipe connected to the rear portion thereof, superheater units connected to the flat bottom of the horizontal chamber of the header and extending downwardly and entering the front extremities of the boiler flues, cylinders for driving the engine having feed pipes extending from the upper portions thereof upwardly to and directly attached to the front wall of the horizontal chamber on opposite sides of the center of the header, drain pipes connected to the said flat bottom of the horizontal chamber between the points of attachment of the superheater units to said bottom and the front wall of the chamber so that the chamber may be drained at a point between the superheater units and the feed pipes leading to the cylinders, the drain pipes extending outwardly, the said drain pipes extending out laterally through opposite intermediate side portions of the boiler and then downwardly exteriorly of the latter to a point below the same between the cylinders, valves in the lower exterior ends of the drain pipes, and mechanism for simultaneously operating the valves to open and close the latter and the said pipes, the exterior location of the drain pipes facilitating the condensation of residual steam permitted to escape therethrough that may pass off with the moisture drained from the header. 95

2. In a locomotive engine, the combination with a boiler having flues, a superheater therein having an upper horizontally disposed header above the flues provided with a supply pipe attached to the rear portion thereof and also having superheater units connected to the bottom of the same and depending to the flues and cylinders for driving the engine having feed pipes extending upwardly therefrom within the boiler and connected to the front end of the header at opposite sides of the center of the latter, of a drain pipe connected to the bottom of the header at each side of the center of the latter between the points of attachment of the superheater units and each cylinder feed pipe, the drain pipes depending from the header through the upper portion of the boiler and then outwardly through the latter to the exterior and downwardly under the boiler, the drain pipes having nozzles at their lower ends provided with valves, and means connected to the valves of the nozzles for simultaneously opening and closing the said valves, the drain pipes permitting the escape of residual steam and water of condensation from 130

the header at points adjacent to the ends of the superheater units attached thereto so that any steam generated and not controllable through the supply pipe connected to the header may be prevented from entering the cylinder feed pipes.

In testimony whereof I have hereunto set

my hand in presence of two subscribing witnesses.

DAVID H. GRIFFITH.
